UNITED STATES PATENT OFFICE.

DANIEL HERLIHY AND MILAN H. FISHER, OF CHICAGO, ILLINOIS; SAID FISHER
ASSIGNOR TO SAID HERLIHY.

WRENCH.

1,349,762.

Specification of Letters Patent. Patented Aug. 17, 1920.

Application filed October 17, 1919. Serial No. 331,448.

To all whom it may concern:

Be it known that we, DANIEL HERLIHY and MILAN H. FISHER, citizens of the United States, and residents of Chicago, county of Cook, and State of Illinois, have invented certain new and useful Improvements in Wrenches, of which the following is a specification.

This invention relates to improvements in that type of wrenches employing a handled shank or bar, having at one of its ends a fixed jaw, with an inner or movable jaw slidably mounted on the shank and adapted for clamping movement and locking action through the instrumentality of a rack bar actuated by a rotary or sleeve nut, and it consists in certain peculiarities of the construction, novel arrangement, combination and coöperation of the various parts thereof, as will be hereinafter more fully set forth and specifically claimed.

As is well known to those skilled in the art to which our invention pertains, difficulty in the adjustment of the movable or inner jaw of wrenches of the above mentioned type, heretofore in general use, which are commonly called monkey wrenches, has been experienced, by reason of the threads of the nut at one side of the unthreaded recess in said nut, for the reception and operation of the toothed part of the rack bar, abruptly contacting with or catching against the sides of said bar or the teeth thereof, or in other words, failing to engage the teeth of the rack bar properly or without impediment.

To avoid or overcome the above mentioned defect or difficulty, and to provide a wrench of such construction and operation of its parts as to afford quick adjustment of the movable jaw thereof, as well as, positive and accurate engaging means for the nice or fine adjustment of the same, is the principal object of the invention.

Another object is to provide means for properly connecting and holding the shank of the wrench in the socket of the handle therefor.

Still another object of the invention is to furnish a wrench of the above mentioned general character, which shall be simple in construction, strong, durable and highly efficient in operation.

Other objects and advantages of the invention will be disclosed in the following description and explanation.

55

In the accompanying drawing, which serves to illustrate an embodiment of the invention,

Figure 1 is a plan view of a wrench embodying one form of the invention showing the jaws thereof slightly separated and the parts in position ready for use.

Fig. 2 is a view in side elevation thereof illustrating by dotted lines one of the positions to which the inner jaw may be moved.

Fig. 3 is a similar view but showing the movable jaw and handle of the wrench in longitudinal section.

Fig. 4 is a cross-sectional view taken on line 4—4 of Fig. 3 looking in the direction indicated by the arrows.

Fig. 5 is a similar view taken on line 5—5 of Fig. 3 looking in the direction indicated by the arrows.

Fig. 6 is an inner end view of the handle showing the shank of the wrench located in the socket thereof and in section but with the rack bar and sleeve nut omitted.

Fig. 7 is a fragmental sectional view of the handle showing a portion of a modified form of the rack bar located in the socket thereof, and

Fig. 8 is an enlarged fragmental plan view of said rack bar.

Like numerals of reference refer to corresponding parts throughout the different views of the drawing.

Referring now more particularly to Figs. 1 to 6 inclusive, the reference numeral 10 designates the shank of the wrench, which is 90 by preference rectangular in cross-section and may be made of any suitable material and desired length. At one of its ends the shank is provided with a jaw 11 which is extended laterally from the shank and with its 95 inner face at a right angle thereto.

Near its other end the shank is provided with an opening 12 for the reception of a tapered screw bolt 13, which is extended through an opening in the handle on one 100 side of the socket therein into an opening located in the other side of the handle diametrically opposite the first named opening, the latter of which openings is screw-

threaded while the other opening in the handle and the opening 12 in the shank are preferably without threads. The handle is designated as a whole by the numeral 14 and 5 may be made of any suitable size, form and material, but by preference of a single piece of metal and cylindrical in shape, as shown.

The handle 14 is provided with a socket 15, which is by preference rectangular in 10 cross-section to receive the similarly shaped shank 10, but may be made of a corresponding shape to the shank if the latter is of another form than rectangular. The socket 15 extends from the inner end of the handle 15 to near its outer end and is provided with a segmental enlargement or recess 16 which extends from the inner end of the handle to near the outer end thereof and is for the reception and operation of a rack bar employed for adjusting the movable or inner 20 jaw of the wrench and for holding and locking the same in its adjusted position, as will be presently explained.

The inner portion of the handle is reduced 25 as at 17, see Figs. 3, 4 and 6 of the drawing. This reduced portion extends from the inner end of the handle outwardly and terminates with a shoulder 18, against which one end of a nut 19 which is in the form of a sleeve or 30 collar rests, the other end thereof being located about flush with the inner end of the handle. The nut 19 is provided with internal screw-threads 20 to engage the teeth 21 of the rack bar 22, which bar is located 35 longitudinally and slidably on that portion of the shank 10 adjacent to the longitudinal recess or enlargement 16 of the handle, as is clearly shown in Figs. 3 to 5 inclusive.

As shown in said figures, the teeth 21 of 40 the rack bar 22 in the form of the invention illustrated in said figures are in the form of true ratchet teeth, that is, each of said teeth has its surface opposed to the movable jaw 23 extended substantially at a right angle 45 to the base of the bar 22, while its face or surface adjacent to the jaw 23 is inclined toward said jaw and toward the base of said bar. It will also be observed in said figures, especially in Figs. 4 and 5, that the bar 22 50 has a portion 24 which overhangs one side of the shank 10, and that the teeth 21 of said bar extend from one edge thereof to the other edge of the same and transversely thereof, yet at a suitable pitch or inclination 55 to correspond with the pitch or inclination of the screw-threads 20 of the sleeve nut 19, which threads engage the ratchet teeth 21 to force the rack bar forwardly and to lock it in its clamping position. The threads 20 60 of the sleeve nut 19 are also in the form of true ratchet teeth, but it will be understood that said threads are not continuous, but each has a registering cut-away portion 25 of sufficient length to extend from one of

the edges of the teeth 21 of the rack bar to 65 the other edge thereof, as will be clearly understood by reference to Fig. 5 of the drawing.

By this arrangement, it is evident that the cut-away portion of the threads 20 in the 70 nut 19 will register with one another and thus form a longitudinal recess within the nut in which recess the rack bar and its teeth can be slid back and forth for quick adjustment without engagement with or interference by the threads of the nut. That end of each of the threads 20 of the nut adjacent to the overhanging portion 24 of the rack bar and of the overhanging part of the teeth thereon is provided with an inwardly 75 extended bevel 26, thus providing a point 27 on each end of the said teeth, which point may have a knife edge presented toward the teeth 21 of the rack bar. By this arrangement it is evident that in turning the 80 nut 19 in the proper direction as indicated by the arrow in Fig. 5, the pointed ends 27 of the threads 20 of the nut will engage the teeth 21 of the rack bar at a slight distance from the overhanging ends of said teeth and 85 that by reason of the knife-like edges of said teeth and the similarly shaped edges of the threads 20 of the nut being presented toward each other, there will be no possibility of the teeth and threads catching or 90 being impeded one by the other in the rotation of the nut to actuate the rack bar.

At a suitable distance from the inner end 95 of the handle 14, the shank 10 is provided with a shoulder 28 in its portion opposite 100 the rack bar. Located around the rack bar between the shoulder 28 and the inner ends 105 of the handle 14 and nut 19 is a collar 29 which is provided with a rectangular opening 30 to receive the shank 10 and said opening has communicating therewith an enlarged recess 31 for the reception of the rack bar and its teeth, which recess is located in a position to register with the recess 16 of the handle as well as with the 110 recess or cut-away portion 25 of the nut 19 when the latter is turned to the proper position as shown in Figs. 3 and 5 to permit free movement of the rack bar and shank.

That surface of the collar 29 adjacent to 115 the nut 19 is provided with a peripheral groove 32 in which is located a stop 33, such as a projecting pin. This stop is employed to co-act with a pin or projection 34 on the end of the nut 19 adjacent to the collar 29 120 so as to prevent more than one revolution of the nut in either direction and so as to act as an automatic guide in holding the cut-away portion 25 of the nut in register with the recess 31 of the collar and with the recess 125 16 of the handle so that quick adjustment of the shank carrying the movable jaw 23 can be effected.

As is clearly shown in Fig. 3, the movable jaw 23 is provided with a longitudinal opening or channel 35 for the reception of the shank 10 and has near its inner end a slot 5 or recess 36 extended laterally from one of the walls of the opening 35 which slot or recess is for the reception and retention of an extension 37 on the end of the rack bar 22 adjacent to the movable jaw.

10 In Figs. 7 and 8 of the drawing, we have shown a modification in the construction of a wrench which consists in employing a rack bar 38 having true V-shaped segmental teeth 39 transversely located thereon instead of the ratchet type of teeth 21 shown in Figs. 1 to 5 inclusive and above described. In this modification the collar 19 is modified in the same respect, that is, the threads 40 thereof are of true V-shape instead of the 15 ratchet type, as in the other construction. Otherwise, the construction of the parts are identical with that shown in Figs. 1 to 6 inclusive and above described.

20 By using the tapered screw-bolt 13 or a similar tapered member for connecting the handle to the shank, it is apparent that the shank can be adjusted with respect to the handle so that the shoulder 28 of the shank will abut against the collar 29 and thus 25 hold it against the adjacent ends of the handle and nut.

Having thus fully described our invention, what we claim as new and desire to secure by Letters Patent is—

35 1. In a wrench, the combination with a shank having a jaw at one of its ends, of a handle mounted on the other end of the shank and having a longitudinally extended opening for the latter and provided with a 40 longitudinally extended recess communicating with said opening, means to secure the handle and shank together, a rack bar mounted longitudinally and slidably on the shank and extended into said recess of the 45 handle, a jaw carried by the rack bar, said rack bar having at one of its edges a part overhanging the shank and provided with transversely disposed teeth of ratchet type 50 extended from one of its edges to the other edge thereof, a nut rotatably mounted on the handle and having segmental screw-threads to engage the teeth of the rack bar, the ends of each screw-thread being sufficiently spaced apart to permit of the free movement of the rack 55 bar there-between, one end of each of said segmental threads being inwardly beveled

and having a knife-like edge presented toward the teeth of the rack bar.

2. In a wrench, the combination with a shank having a jaw at one of its ends, a 60 transverse opening near its other end and a shoulder between said opening and jaw, of a handle mounted on the end of the shank opposite its jaw and having a longitudinally extended opening for the shank and provided with a longitudinally extended recess 65 communicating with said opening, said handle also having transverse openings to register with the opening in the shank, a tapered member located in said openings for holding the shank and handle together and for longitudinally adjusting the former in assembling the same, a rack bar mounted longitudinally and slidably on the shank and extended into said recess of the handle, a 70 jaw carried by the rack bar, a nut rotatably mounted on the inner end of the handle and having segmental screw-threads to engage the teeth of the rack bar and provided with a projection on one of its ends, and a collar 75 mounted on the rack bar and shank between the shoulder of the latter and the nut, and having on its face adjacent the nut a stop to engage the projection on the latter.

3. In a wrench, the combination with a shank having a jaw at one of its ends, of a handle mounted on the other end of the shank and having a longitudinally extended opening for the latter and provided with a longitudinally extended recess 80 communicating with said opening, means to secure the handle and the shank together, a rack bar mounted longitudinally and slidably on the shank and extended into said recess of the handle, a jaw carried by the rack bar, said 85 rack bar having at one of its edges a part overhanging the shank and provided with transversely disposed teeth of ratchet type 90 extended from one of its edges to the other edge thereof, a nut rotatably mounted on the handle and having segmental screw-threads of ratchet teeth type to engage the teeth of the rack bar, the ends of each screw-thread being sufficiently spaced apart to permit of the free movement of the rack bar there-between, and one end of each of said segmental 95 threads being inwardly beveled and having a knife-like edge presented toward the teeth of the rack bar.
